DESIGN FOR A COMBINATION LOVE SEAT,
LOUNGE, AND BED

Robert N. Eisendrath, Chicago, Ill.

Application May 15, 1947, Serial No. 139,045

Term of patent 14 years

(Cl. D15—11)

To all whom it may concern:

Be it known that I, Robert N. Eisendrath, citizen of the United States, residing at 5465 Hyde Park Boulevard, Chicago, in the county of Cook and State of Illinois, have invented a new, original, and ornamental Design for a Combination Love Seat, Lounge and Bed, of which the following is a specification, reference being had to the accompanying drawing, forming part thereof.

Fig. 1 is a front elevational view of a combination love seat, lounge, and bed, showing my new design.

Fig. 2 is an end elevational view thereof.

Fig. 3 is a front elevational view thereof with one of the end members in its raised position.

Fig. 4 is a front elevational view with both end members in their raised position.

Fig. 5 is an end elevational view of Fig. 4.

Fig. 6 is a top plan view of Fig. 1 and

Fig. 7 is a perspective view thereof.

I claim:

The ornamental design for a combination love seat, lounge, and bed, as shown.

ROBERT N. EISENDRATH.
